United States Patent Office.

JAMES W. EPPERSON, OF WOODHULL, ILLINOIS.

Letters Patent No. 66,008, dated June 25, 1867.

FARM-GATE.

The Schedule referred to in these Letters Patent and making part of the same.

TO ALL WHOM IT MAY CONCERN:

Be it known that I, JAMES W. EPPERSON, of Woodhull, in the county of Henry, and State of Illinois, have invented a new and useful improvement in Farm-Gates; and I do hereby declare that the following is a full, clear, and exact description of the same, reference being had to the annexed drawings, making part of this specification, in which—

Figure 1 is a front elevation; and

Figure 2 is a side elevation and section.

The same letters are employed in the designation of identical parts in both figures.

A represents a panel of fence adjoining the gate-way, supported upon posts A': B is the post against which the gate closes. Wheels C are attached to the posts A' A', so as to turn freely upon their axes. D is the gate, which is formed of two parallel horizontal rails, to which the vertical strips D² are attached in such manner that their rounded ends shall extend above the top rail D¹, as shown in fig. 1. The gate is hung upon the wheels C C, a groove being cut in the lower edge of the rail D¹ to receive the edge of the wheels C C. The gate may be slid easily upon these wheels, so as to close or open the gate-way. This is effected by means of the spur E, which is made with four arms, rounded upon their ends, turning against the projecting upper ends of the strips D², which must be placed at such distance apart as to mesh into the spaces between the arms or cogs of the wheel E in opening or closing the gate. This spur-wheel E is attached to a horizontal shaft, E', which is set perpendicular to the line of fence, and turns in suitable bearings on the posts G G, and an intermediate support, G', attached to the fence.

The gate is operated in opening and closing by the winches F F, which are so placed by the side of the track that they may be easily reached by persons riding either on horseback or in a vehicle. I place pins H above the rail D¹ to preserve its alignment, and cause the ends of the horizontal rails also to shut into recesses in the post B.

What I claim as my invention, and desire to secure by Letters Patent, is—

1. The spur-wheel E, operating substantially as described.
2. The grooved rail D¹ of the gate D, in combination with the spur-wheel E and the revolving wheels C, attached to the fence posts, and upon which the gate slides in opening and closing.
3. In combination with the gate D, with horizontal rail D¹ and vertical strips D², I claim the spur-wheel E, shaft E', and winch F, arranged to operate substantially in the manner and for the purpose set forth.

In testimony whereof I have signed my name to this specification in the presence of two subscribing witnesses.

JAMES W. EPPERSON.
